UNITED STATES PATENT OFFICE

PAUL M. HOENSHEL, OF MIAMI, FLORIDA, ASSIGNOR TO MAYACA COMPANY, OF MIAMI, FLORIDA, A CORPORATION OF FLORIDA

COMBINED IRRIGATION AND DRAINAGE PUMP

Application filed May 31, 1928. Serial No. 281,754.

This invention relates to a combined irrigation and drainage pump.

The object of my invention is the construction of an efficient pump for furnishing a water control system for small units of land enclosed by dikes, the apparatus being used to pump water from a main water control ditch located outside the dike onto the land for irrigation, and, reversed, to pump water from the land into the control ditch for drainage.

Another object of my invention is the construction of a peculiar and efficient pump which has its discharge point located on a level with the bottom of the ditch, whereby water in the main casing of the pump is never raised an inch more than necessary. Water is raised in the vertical casing of my apparatus just high enough to cause a flow through the culvert line into the discharge ditch and no more. As water in the discharge ditch rises, the pump automatically lifts the water level in the vertical casing enough to overcome it. This results in a considerable saving in power required to pump a given quantity of water, with no sacrifice of pumping range.

Owing to the reversible feature of my pump, it can be used as a drainage pump by merely changing the twist of the driving belt, which reverses the rotation of the propeller blades and thrusts water down and out of the vertical casing instead of lifting it. Water is thus drawn through the culvert line and forced into the main water control ditch, even though its level be considerably higher than that of water inside the dike.

Further, by reason of my peculiar apparatus, as water is carried through the dike at ditch level, by throwing off the drive belt and allowing free rotation of the propeller blades, the pump can be used as a gravity drain with only a nominal loss of efficiency.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention.

Figure 2 is an enlarged view in side elevation, of my improved pump.

Figure 3 is a sectional view taken on line 3—3, Figure 2, and looking in the direction of the arrows.

Figure 4 is a vertical sectional view taken on line 4—4, Figure 2, and looking in the direction of the arrows.

Figure 5 is a top plan view of the pump.

Figure 6 is a vertical sectional view taken on line 6—6, Figure 4, and looking in the direction of the arrows.

Figure 7 is an enlarged side view taken on line 7—7, Figure 2 and looking in the direction of the arrows.

Figure 8 is a sectional view taken on line 8—8, Figure 7, and looking in the direction of the arrows.

Referring to the drawings by numerals, 1 designates the support or framework, comprising the vertical uprights 2 carrying the horizontal beams 3, and the uprights are suitably braced by crossed pieces 4. Suitably braced upon the beams 3 are vertically extending uprights 5 that are provided with a cross piece 6, for the purpose hereinafter specified.

A vertical primary casing 7 is positioned between the uprights 2 of the framework or support 1, and this casing is entirely suspended above the bottom of the main water control ditch 8 by preferably a pair of horizontal angle brackets 9. Each bracket 9 is L-shape in cross section, Fig. 4, with the vertical flange fixedly secured to the casing 7, and the horizontal flange notched at 10, in a plurality of places, for receiving the vertical uprights 2, as clearly shown in Figure 3. Suitable fastening means 11 is driven through the vertical flange of each bracket 9 into the uprights, whereby the pump is securely suspended upon the framework. The notching of the angle brackets 9, for receiving the uprights, produces a very efficient and durable structure, as all of the uprights are "locked" together by these metal horizontal brackets.

Attached by suitable means to the lower end of casing 7 is a substantially U-shape bracket 12; this bracket serving two functions, to wit: it supports the lower thrust socket collar bearing 13, as well as the horizontal bracket 14, Fig. 2. Fastened to the under face of beam 6 is an upper thrust socket collar bearing 15. The ends of rotatable shaft 16 are journalled in these collar bearings 13 and 15. A belt wheel or pulley 17 is securely fastened on shaft 16 with a belt 18 thereon. This belt 18 may be twisted for reversing the movement of the shaft 16 or by removing the belt entirely off pulley 17, the shaft may idle. Propeller blades 19 are fastened to the shaft 16 near bearing 13 and washer 20 is interposed between the upper end of bearing 13 and blades 19. A ring 21, L-shape in cross section, is permanently fastened in the upper end of the casing 7, and on the horizontal flange of this angle ring (Fig. 4) is securely fastened the cover plate 22. This cover plate is welded at 23, to the "pipe" housing 24 within which housing is a bronze "block" or sleeve 25. Hard bronze washers 26 are placed at the ends of housing 24 and sleeve 25 (Fig. 6) and against these washers, on shaft 16 are thrust collars 27, whereby shaft 16 can rotate freely within the casing 7, but the casing and its peculiarly constructed "head" will remain stationary.

One of the several important features of my improved irrigation and drainage pump is the formation of a culvert-receiving casing 28 at approximately the center of the main casing 7; this horizontal culvert-receiving casing 28 is used as a discharge or suction inlet of the pump, because the inner end of the culvert pipe line 29 extends into the casing 28, so that when water is being pumped into the irrigating ditch 30, the horizontal casing 28 serves as an outlet, whereas when the pump is serving as a drainage apparatus, the casing 28 acts as a suction or inlet unit, for the water to enter the main casing 7 and pass out through its bottom. It is to be noted that the whole of my pump is suspended clear of the ditch, with the lower bearing for the rotary shaft supported upon the depending bracket 12.

At the outer end of the culvert pipe line 29, within the irrigation ditch 30 (which may also be a drainage ditch), I preferably place a gate-valve device 31. It will be seen upon referring to Figure 1, that the discharge point of the pump is located on a level with the bottom of the ditch 30. Therefore, water is never raised an inch more than necessary. Further, should the water be raised above the casing 28, there is an "expansion" chamber formed in the upper part of casing 7, but only in extreme cases is the water raised higher than just sufficient to flow through the culvert line into the discharge ditch, and no more. As stated before, this results in a consider-

able saving in power to pump the given quantity of water, with no sacrifice in pumping range. Therefore, this new idea of placing the outlet on the main pumping casing at approximately the center, and on a line with the bottom of the irrigation or drainage ditch is an important feature of my invention. 70

A grease cup 32 is connected to housing 24 and a second grease cup 33 is fastened on the upper end of "grease line" or pipe 34. This pipe extends downwardly through horizontal brackets 35 and 14. Then the pipe 34 extends through a horizontal aperture 36 (Fig. 8) and connects to the bearing 13, fastened to the U-shape bracket 12. By placing a lubricant in 80 grease cup 33, the lower end of the pump will be efficiently lubricated. Therefore, it will be seen that U-shape bracket 12 very efficiently mounts the lower end of the grease line 34 on the pump, while at the same time supporting 85 the lower end of rotary shaft 16, all free and above the bottom of the main ditch.

As indicated by dotted lines A in Figure 1, it is within the scope of this invention to extend the culvert pipe lines in opposite directions, so that water may be discharged into a number of irrigating ditches at preferably the lower part thereof, or equally as well a number of drainage ditches may be drained completely by the water passing from the 90 bottom of the ditch or ditches into the main casing 7, and thence into the main ditch. 95

My pump may be placed in any part of the main ditch for best results, by building the framework so that the pump is suspended entirely thereon, above the bottom of the ditch, with its discharge line positioned for supplying water to or draining water from the bottom of each and all irrigating ditches, or drainage ditches with which the pump is connected up, this being accomplished by the peculiar manner hereinbefore described, of forming the horizontal casing 28 and the horizontal culvert pipe line 29. 100 105

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such alterations or changes as shall fairly fall within the scope of the present invention. 110 115

What I claim is:

1. In an apparatus of the class described, the combination with vertical uprights, of a main casing between said uprights, horizontal brackets L-shape in cross section fastened intermediate their ends to the outer face of said casing, said brackets provided near their ends with notches in the horizontal flanges, said vertical uprights positioned in said notches, fastening means extending through the vertical flanges of the brackets into said 120 125 130

uprights, said main casing provided with pipe or culvert receiving means on its side, and water propelling means within said casing.

5 2. In an apparatus of the class described, the combination of a main casing, a ring L-shape in cross section fastened in the upper end of said casing, a cover plate fastened to the horizontal flange of said L-shape ring, 10 a housing extending through said cover plate and fastened thereto, a sleeve within said housing, a bracket fastened to the lower end of said casing, a bearing on said bracket, a shaft with blades journalled at its lower end 15 in said bearing and extending through said sleeve, and said main casing provided with an inlet and an outlet on its side.

3. In an apparatus of the class described, the combination of a casing closed at its upper end and open at its lower end, a substantially U-shape bracket fastened across the lower open end of said casing, a bearing secured upon said bracket, a shaft with blades journalled at its lower end in said bearing 20 and extending through the upper closed end of said casing, and a pipe or culvert receiving casing on said first mentioned casing between its upper and lower ends.

4. In an apparatus of the class described, 30 the combination of a casing provided with a bracket secured to opposite portions of its sides and across its bottom, a bearing fastened upon said bracket, a bracket fastened to the upper portion of said casing, a second bracket fastened to the first mentioned bracket, a grease pipe extending through said bracket at the upper portion of the casing and through said second bracket and connected to said bearing, said grease pipe also 35 extending through the first mentioned bracket, a shaft provided with blades journalled in said bearing and extending beyond the upper end of said casing, and a culvert receiving casing fastened to the side of said first 40 mentioned casing.

45 In testimony whereof I hereunto affix my signature.

PAUL M. HOENSHEL.
